PUMP CONSTRUCTION

Edmund H. Blunt, Brooklyn, N. Y.

Application February 3, 1930, Serial No. 425,663
Renewed January 13, 1934

12 Claims. (Cl. 103—49)

My invention relates to improvements in pumps and particularly to what are commonly termed steam driven direct acting pumps. This application is a continuation in part of my application 604,414 filed Dec. 1, 1922, and now Patent 1,745,597 dated Feb. 4, 1930, in which I have claimed a feed water heater but which patent discloses a combination of two steam driven pumps having certain features of construction 5 which may be employed for other purposes than in a feed water heater.

One object of the present invention is to provide a pair of steam driven pumps in which the pistons are capable of operating against a greater pressure when moving in one direction than when moving in the opposite direction.

Another object is to provide a construction of this character in which the two pistons are capable of operating against a greater pressure when 20 moving in one direction than when moving in the opposite direction.

Another object is to provide a construction of this character in which the two pistons although movable simultaneously in opposite directions arrive at the ends of their strokes more quickly 25 when moving in one direction than when moving in the opposite direction so that one piston will usually remain stationary and wait for the other piston to reach its end of the stroke in the opposite direction. The two pistons are thus synchronized at the start of each stroke although one may arrive at the end of its stroke before the other.

Another object is to provide means for cushioning the pistons at the end of a pumping stroke so as to insure the gradual slowing down of the piston and prevent shock.

In the construction as herein illustrated the pumps are intended to handle liquids and the power is supplied by steam. There are two units each consisting of a pump cylinder and piston and a steam cylinder and piston. The pistons of each unit are connected by a common piston rod which passes through the adjacent ends of the steam and pump cylinders. The steam is supplied to the steam cylinders through a main valve of conventional type which is controlled by a single auxiliary valve arranged transversely on the top of the steam cylinders. This auxiliary valve is mechanically actuated by tappets connected to the respective steam piston rods.

In the particular structure shown the pump units receive liquid alternately from a common source through intake valves at a suitable pressure and these pistons alternately discharge this

liquid through common valve passages at substantially the received pressure. The opposite ends of the pump pistons are of greater area and intended to alternately receive liquid from a common source and discharge this liquid alternately through a common port or ports but at a materially greater pressure than the pressure at which the liquid is received. This unequal pressure of discharge at the opposite ends of the pump pistons obviously requires a special valve 10 for supplying steam pressure appropriate for the work to be done.

In this case, for instance, the pump units are arranged with vertical piston rods and the steam pressure employed to force the pistons down may 15 be for instance, 250 pounds to the square inch, whereas the pressure required for lifting the pistons may not exceed 50 pounds per square inch. This difference in pressure may be acquired in various ways, for instance, by use of a 20 reducing valve of conventional type interposed in the passage for the steam to the lower sides of the steam pistons.

Such a construction is admirably adapted to the handling of two different liquids or fluids at 25 the same time with such appropriate volumetric ratio as may be necessary.

One instance of such use is that of my former Patent 1,745,597 where the pump draws in a certain volume of cold water in the upper ends of 30 the pump cylinders and forces that cold water into a feed water heating chamber, while the opposite or lower ends of the pumps receive a larger volume of hot water from the heater vessel and force it into the boiler. In this case the 35 difference in volume of the cold and hot water is of course made up by the steam which is condensed within the vessel. The upper ends of the pumps will in such case be receiving water under the comparatively low head due to the height 40 of the water tank of a locomotive and forcing this cold water into the heater vessel against the pressure of what would ordinarily be the exhaust steam used to heat the heater vessel. The lower ends of the pumps will of course be receiving hot 45 water from the heater vessel under the head due to this height above the pump suction valves, whereas the lower ends of the pumps must discharge this heated water against boiler pressure. So far as the present invention is concerned, 50 however, the mechanism might be employed for handling different liquids or liquids containing chemicals to be mixed.

Fig. 1 shows a part sectional and part side elevation of a combined or twin unit pump with the 55

necessary valves and conduits and also one type of steam operating mechanism.

Fig. 2 is a side elevation of the right hand pump shown in Fig. 1 partly in section on the 5 plane of the line 2—2.

Fig. 3 is a sectional view of the combined stuffing box and water cushioning device of Fig. 1, showing details of preferred construction.

Figs. 4 to 19, inclusive, show details of a modification of the steam valve control of Figs. 1 and 2.

Fig. 4 is a section of an auxiliary synchronizing steam valve taken on the plane of the line 4—4 of Fig. 11.

Fig. 5 is a section taken on the plane of the line 5 of Fig. 11.

Fig. 6 is a section taken on the plane of the line 6 of Figs. 15 and 16.

Fig. 7 is a section through the synchronizing 20 valve taken on the plane of the line 7 of Figs. 15 and 16.

Fig. 8 shows a top plan view of a pair of steam cylinders with the preferred form of steam valves parts being shown in section.

Fig. 9 is a side elevation, partly sectioned, of the same steam cylinders and shows the mounting of the regulating synchronizing valve 75 on top.

Fig. 10 is a horizontal sectional view on the 30 plane of line 10—10 in Fig. 9 and plan of the preferred type of synchronizing valve in the first position of its pumping cycle.

Fig. 11 is a vertical sectional elevation of the 35 same valve in the same position as in Fig. 10, a section being taken on the plane of the line 11—11 of Fig. 8.

Fig. 12 is a vertical sectional elevation of the left hand tappet-rod valve, on the plane of the line 12—12 of Fig. 8.

Fig. 13 is a sectional plan showing the synchronizing valve in its second position.

Fig. 14 is a sectional plan of this valve in its third position.

Fig. 15 is a sectional plan of the same valve 45 in its fourth position.

Fig. 16 is a sectional elevation of the valve in the same position.

Fig. 17 is a sectional plan of the synchronizing valve in its fifth position.

Fig. 18 is a sectional plan view of this valve 50 in its last or sixth position.

Fig. 19 is a left end view of same valve on the line 19—19 of Fig. 10.

In the form shown in Fig. 1 the pump cylinders 55 1 and 2 are arranged side by side and are provided with pistons 3 and 4 having piston rods 5 and 6 respectively. These piston rods may have sleeves such as 5a and 6a. The pump cylinders are provided with an upper head 7 and a lower head 7''. The upper ends of the pump cylinders are provided with a supply pipe 8 and suction valves 9 between the supply pipe and the chamber 10 which connects the upper ends of the two cylinders. Each pump cylinder is provided with 60 a discharge valve 11 which is preferably of the multiple beat type and controls the discharge of liquid through the conduit 12, for instance, to a spray head of a feed water heater connected to the outlet 13 as set forth in my Patent 65 1,745,597.

Fig. 2 shows the two chambers 10 and 10A and the discharge valve 11 and 11A for the two pumps. Valve 11A discharges through pipe 14 which is connected to conduit 12.

70 The lower end of the pump has an intake or

supply pipe 15 discharging into the chamber 16. The right hand pump cylinder is provided with intake or suction valves 17 and the left hand cylinder is provided with suction valves 23. The lower ends of the cylinders are provided with outlet passages 24 leading to chambers 20 and 20A on opposite sides which are connected by a passage 25. The chambers 20 and 20A may be provided with separate cover plates 26.

5 Valves 19 control the discharge of water from the lower ends of the pump cylinders to the chambers 20 and 20A and the discharge members 21 and 22. Portions of the pump cylinder head 7 extend downwardly in the form of flanges 27 forming stuffing boxes for the piston rods and 15 providing cushioning means which will be described hereinafter.

A casting 28 forms a bridge resting upon the head 7 and in turn supporting the plate 31 which forms the lower heads of the steam cylinders 20 29 and 30. Stuffing boxes 32 guide the piston rods through the lower heads of the steam cylinders. Steam piston 33 is secured on the upper end of the piston rod 5 and is loosely connected to a tappet-rod 34 in a well known manner. A button 35 on the lower end of the tappet-rod is adapted to engage a plate 36 on the top of the piston 33. Enlargement 36A on the upper part of the tappet-rod is also adapted to engage the plate 36. 30 Piston 33a is secured to piston rod 6 and travels in the steam cylinder 30. The upper ends of the steam cylinders are provided with a plate 37a which provides the usual heads for the steam cylinders.

A steam actuated main valve 81, contained in 35 a casing 38, supplies the operating steam to the top of one steam cylinder and to the bottom of the other cylinder simultaneously, and vice versa. This valve is similar to that used by locomotive air compressors and is shown in vertical section 40 (Figs. 1 and 2) and in horizontal section (Fig. 8). A steam port 85, within casing 38, connects by a passage 85a to the top of steam cylinder 29 and also through a pressure reducing valve similar to 44 of Fig. 2, it connects with conduit 45 45 and the bottom of cylinder 30.

The main valve for controlling the admission and exhaust of steam is of a conventional type as shown in my Patent 1,745,597. One form is shown in Figs. 1 and 2 and at the right of Fig. 8, although the latter figure shows a modification of other details. The valve receptacle 38 is secured on one side of steam cylinder 29. This has a valve seat 38a which supports a slide valve 81. This slide valve is connected to a stem 83 which 55 has pistons 82 and 84 of unequal areas on opposite ends as shown in Figs. 2 and 8.

Steam is admitted to the valve chamber from pipe 41. If desired, a steam throttling device or governor 42, of conventional type may be interposed and connected by pipe 43 to a pressure regulating supply (not shown).

A valve housing 44 and pipe 45 provide a conduit for connecting the main valve chamber with the lower end of the cylinder 29. This conduit contains a reducing valve 46 mounted on a stem 47. This may be adjusted by the nut 48 to regulate the permissible closing of the valve. The stem is guided in a spider 49.

This permissible closing regulates the live steam 70 pressure to the bottom of each main piston but the valve 46 is free to rise, allowing a rapid escape of the exhaust steam whenever the down stroke of the pump has been reversed.

The steam port 85 (Fig. 8) connects through 75

passage 85a to the top of the right hand steam cylinder 29. The passage 85b is an extension from port 85 to the bottom of the left hand steam cylinder 30 through a pressure reducing valve 5 similar to that shown in Fig. 2 and above described.

Port 86 is connected to the bottom of the steam cylinder 29 past the reducing valve 44 and the pipe 45 above described. Port 86 (shown in Fig. 10 8) is also connected through conduit 86a to the top of the left hand steam cylinder, in the usual manner.

Port 87 allows exhaust through pipe 87a and alternately connects with ports 85 and 86 in the 15 usual manner. The space between the two pistons 82 and 84 is filled with live steam so that on account of the greater area of the piston 82 the tendency of the live steam pressure is to force the valve carrying pistons to the left or in the 20 direction of piston 82.

The admission and exhaust of steam to and from the main valve above described may be accomplished in various ways, for instance, as shown and described in my Patent 1,745,597. 25 Such a valve shifting mechanism is shown diagrammatically in Fig. 1 where an auxiliary valve is mounted on the top of the steam cylinder head and has two parts, 37 and 37a, moved back and forth transversely by tappet-rods 34 and 34'. 30 These tappet-rods have pins 34a and 34b on their upper ends which extend into inclined or offset slots 40a and 40 respectively, which are formed as a part of the valve members 37a and 37, so that the valve members are reciprocated horizontally by the vertical movement of the tappet-rods. 35

Details of such valve mechanism in a modified form will be described hereinafter in connection with Figs. 4 to 7 and 8 to 19 respectively.

40 The operation of the mechanism thus far described is as follows:

Live steam is admitted through the pipe 41 to the main valve in the casing 38 and passes through port 85 and passage 85a to the spaces 45 above the piston 33. This forces the steam piston 33 downwardly and with it the pump piston 3. The downward movement of the piston 3 draws water through the pipe 8 past the valve 9 into the chamber 10 and thus into the upper 50 part of the cylinder 1. At the end of the down stroke of the piston the tappet 34 is drawn downward by the piston 33 and the pin 34a slides downward in the slot 40a and moves the valve 37a to the right as viewed in Fig. 1. While steam is 55 being admitted above the piston 33 it is also being admitted beneath the piston 33a at a reduced pressure through a reducing valve such as illustrated in Fig. 2 (but not shown in connection with the left hand cylinder). The rising piston 60 33a at the upper end of its stroke forces the tappet 34' upwardly so that its pin 34b sliding in the slot 40 moves the valve 37 to the left. When these two valves are set as just described an auxiliary steam passage 88 to the main valve leading 65 in to the left hand side of the piston 82 as viewed in Fig. 2 is opened and live steam then forces the piston 82 and valve member 81 to the right as viewed in Fig. 2 so as to close the port 85 and shut off the steam to the upper end of the piston 33 and the lower end of the piston 33a. As the piston 33 rises it of course lifts the pump piston 4 and draws liquid through the conduit 15 into the chamber 16 and past the valves 23 into the space beneath the piston 4.

70 When the valve port 85 is closed the valve port

86 is opened and live steam passes through passage 86a, Fig. 3, to the top of the left hand piston in cylinder 30 and at the same time through the reducing valve 46 shown in Fig. 2 to the bottom of the right hand steam cylinder 29 thus reversing 75 the action of the steam pistons and pumps as above described. As the pump piston 3, Fig. 1, rises the water above it is forced out into the chamber 10 and through valve 11 to the discharge conduits 12, 13. At the same time the pump 10 piston 4 is being forced downwardly by steam piston 33a and the water below the left hand pump piston is forced upwardly through passages 24 and 18 and valves 19 into chamber 20 and thence out through passages 21, 22. It will be 15 seen that the effective area of the lower face of each of the pumping pistons is greater than the area of the upper face so that on the down stroke of each piston a greater volume of water is handled than on the up stroke. The difference 20 in volume can be determined by using such cross sectional area of piston rod (or sleeve) as would produce the necessary difference in volume.

The use of reducing valves 44 above described provides a materially less steam pressure for the 25 up stroke of the steam pistons and of course a correspondingly reduced steam consumption. As the pressure against which the pump pistons discharge on the up strokes is much less than the pressure against which the pumps discharge 30 on the down strokes, the up stroke can be made at a higher velocity and consequently a piston may reach the upper end of its stroke before the companion piston reaches the lower end of its stroke and vice versa. Each piston, 35 however, must remain at the end of its stroke until the other piston has arrived at the end of its stroke before steam is admitted to start the next stroke.

In Fig. 3 I have shown the preferred form of 40 construction of pump cylinder stuffing box and piston. The cylinder 2 is provided with a bushing 60 forming the inner wall in which the piston 4 slides. This bushing is provided with passages 24 leading to the conduit 15. The 45 lower end of the piston has a flange 58 provided with passages 58a so that as the flange gradually closes the passages 24, air which may be trapped beneath the piston can escape. The head 7 carries a depending flange 51a having passages 56a, and the piston 4 has a flange 4a adapted to pass beyond the flange 51a at the upper end of the stroke. Liquid trapped between the piston and the flange 51a escapes slowly through the 50 passages 56a, thus producing a cushioning action and permitting the piston to move at high speed throughout practically its entire stroke, inasmuch as the end of the stroke is cushioned gradually.

In case a sleeve 6a is to be employed on the piston rod 6, a stuffing box 51 may be provided having a screw cap 52 with an inner flange 53 adapted to bear on a split gland 54, these parts being secured together. Different sizes of glands 65 may be provided to fit different sizes of sleeves. A split filler 55, adapted to different sized sleeves is used to retain the packing.

In Figs. 4 to 19, inclusive, I have shown a special form of auxiliary valve mechanism for 70 controlling the action of the steam pistons and the connected pump pistons so that each pump piston can move upwardly at a somewhat faster rate than downwardly and yet ensure the simultaneous starting of both pistons. The pistons 75

33x and 33y in Figs. 8 and 9 happen to be of different diameters but this is immaterial.

For the purpose above mentioned, I interpose a secondary steam controlling valve, hereafter called a modified synchronizing valve in the casting 75 which is preferably mounted on the upper steam cylinder head, as shown in Figs. 8 and 9. Its horizontal travel is essentially the same as that of the valves 31 and 31a of Fig. 1.

10 The valve casing 75 contains two horizontally movable piston valves with a central valve body between. The right hand valve 76 is moved by an outer piston 77 which is steam-operated and connected to 76 by stem 77'.

15 This valve 76 is attached to the cylindrical central valve 78 which covers and uncovers a number of small steam ports 100, 102, 104, 105, 106 and 107. Further to the left the valve 79, similarly operated by a steam piston 80 to which it is attached, is free to move horizontally with respect to valve 78.

20 These outer valves shift horizontally whenever their associated tappets 90 and 91 rise, and operate the respective valves within the casings 90a and 91a, thus reversing their travel when the tappet-rods fall. This gives four possible combinations of pistons positions for the passing of small amounts of steam through the center valve 78 and the ports 100, 102, 104, 105, 106 and 107, 30 though only two combinations of pistons are formed and required should the two pistons stop simultaneously.

35 I meet these conditions by rotating the center valve 78 during the cycle, and so opening two extra ports whenever needed.

40 The main steam valve has already been described in connection with the operation of the form shown in Figs. 1 and 2, although it is a conventional structure and is generally familiar to those skilled in the art.

Starting with Fig. 8, it will be seen that the passage 88 connects port 88a of the main steam valve chamber with port 104 in the auxiliary or synchronizing valve 75. Port 104 is connected to port 100 by passage 75x in the wall of the valve casing 75.

45 Live steam passage 89 supplies steam direct to the casings of valves 90a and 91a. Passage 89 is also connected to ports 114 and 115 by passages 114x and 115x. Passage 89 is also connected to ports 106 and 107 by passages 106x and 107x. Passage 106x is shown in Fig. 7 and passage 107x in Fig. 5.

50 Valve casing 91a (Fig. 8) is connected to port 113 by passage 112 and valve casing 90a is similarly connected to port 111 by passage 110.

Ports 102 and 105 at times exhaust through passage 103 to the atmosphere.

55 Valve casing 91a has an exhaust passage 116 to the atmosphere (Fig. 12) and valve casing 90a has a similar exhaust passage (not shown). Interior valves 90B and 91B, operated by their respective tappet rods, are of slide valve construction and each alternately allows live steam to 60 pass to the outer ends of the auxiliary valve 75, and later escape to the atmosphere.

65 Passage 88 is connected to port 58a in the main valve casing 38 so that exhaust from 88 to the atmosphere, will relieve pressure on the outer 70 face of piston 82 and cause the attached valve member 81 to travel towards 58A, due to the unbalanced steam pressure on the unequal inner areas of pistons 82 and 84, Fig. 8.

75 Tappet-rods 90 and 91 moving their respective slide valves 90B (Fig. 9) and 91B (Fig. 12) in

the usual manner admit or release steam to and from the outer ends of the pistons 77 and 80 through passages 110 and 112 as shown in the cylinder head. Live steam pressure is always maintained between piston 77 and valve 76. 5 With live steam supplied to the outer faces of 77, the unequal piston areas keep the two at the left, as shown in Figs. 10 and 11, but x when steam is exhausted through 111 and valve 90B, the pistons shift, as in Fig. 5. 10

In Figs. 15 and 16 a complete assembly of the parts within the synchronizing valve casing 75 is shown. For instance, with the rod 91 pulling down the side valve 91B, Fig. 12, live steam supplied to recess 89A by passage 89, flows through 15 112 and port 113, driving piston 80 to the right, as in Fig. 10.

When rod 90 lifts valve 91B, the port to 112 is protected from the live steam, and connects by an interior passage of 91B with the outlet port 20 of 116, allowing steam to escape through port 113 to the atmosphere, the piston 80 shifting to the left, as in Fig. 15. Piston 77 may have two split packing rings 117. Valve 76 may have similar packing rings, as is customary. Central valve 78 25 has two outer portions with broad split rings 118 and two narrow split rings 119 on the inner portion of the valve, while between them is located the steam slot 118a. The casing 75 may have removable bushings or linings such as 120 and 30 121. In the upper part of bushing 120 there are located steam balance ports 121, at times diametrically opposite the ports, 103, 107, 104, 106. A steam passage 123 through rotating valve 78 connects 122 at times with circumferential slot 35 101, as shown in Figs. 5, 7, 11, etc.

The left valve 79, shown specifically in Fig. 15, has a hollow extension 92 with a curved slot 93 in which travels a pin 94 attached to a stem 95 which is firmly attached to the central valve 78 40 45 by a nut 96 (Fig. 17).

Within the slot 93 is shown a double row of arrows and small circles 97 that show the relative direction and travel of pin 94 and the possible locations where the pin would stop for each 45 of the six possible positions as herein defined.

50 Valve 79 has a key or lug 98 (see Fig. 4) traveling in a slot 99 in the valve casing, thus preventing 79 from revolving. Central valve 78 and the attached rod 95 are free to rotate and also to slide horizontally, being forced to rotate by the pin bearing against the curved walls of the groove 93.

In a complete pumping cycle of two pumping units having opposing strokes I have six possible 55 combinations or positions of the two pump pistons, as to which one first finished the stroke. They are here named in their natural order, as the first, second, third, fourth, fifth and sixth positions.

The first and fourth positions are the operating ones while the others are intermediate. For instance the interior valves of 75 might jump from the first directly to the fourth position and immediately reverse the main steam valve 38. Or they 65 might go from first to second with no results, or from first to third and no reversal would occur. A like condition occurs between the fourth and fifth and sixth positions.

In the first position as shown in Figs. 10 and 11, 70 4 and 5, any steam contained in passage 88 follows the arrows through 75x to port 100, slot 101 in the valve 78, then to port 102, and escape passage 103, to the atmosphere, all the other ports under valve 78 being then closed. 75

5 Valve 78 having shut off the live steam supply to passage 88 and allowed the escape of steam from port 58a, Fig. 8, so that the unbalanced pressure of steam on the opposite side of piston 82 moves slide valve 81 to the left as shown. This 10 opens port 85 and admits high pressure steam on the top of piston 33x and reduced pressure steam underneath piston 33y. The right hand piston 33x therefore descends and the left hand piston 33y rises. Should the rising left hand piston 33y be the first to end its stroke, its tappet 91 will raise slide valve 91B, cutting off the live steam supply 15 from chamber 89A to passage 112, and thereby exhausting steam through port 113, passage 112, and valve 91B, into passage 116 to the atmosphere (Figs. 10 and 12). Unbalanced pressure between 20 79 and 80 causes them to shift to the left, forming the second position, Fig. 13. Valve 78 does not shift, slot 101 remains as before, passage 88 is open to the atmosphere and the main steam valve 81 keeps its position, as shown in the first position.

Should the falling right hand piston 33x end its stroke first, the tappet 90 draws down valve 25 90B, allowing steam to escape through port 111, passage 110 and slide valve 90B to the atmosphere.

This is the third position (Fig. 14), wherein 30 valve 79 remains at the right but steam escaping through port 11, allows valves 76 and central valve 78 to shift to the right; the slot 101 now registers with ports 104 and 105, the latter connecting with passage 103 and the steam from 88 escaping to the air and the main valve 81 remaining as in the first position.

35 But when the left piston 33y reaches the top and the right piston 33x reaches the bottom, either at the same time or otherwise, then position four is reached and the slide valves 91B and 90B are shifted to allow steam to escape from the outer faces of pistons 80 and 81, causing them to move apart, as shown in Figs. 15 and 16. During the subsequent positions five or six (Figs. 17 and 18), the synchronizing valve 75 will allow live steam to pass from 89 to 88 and by its unbalanced pressure on piston 82 will shift main valve 81 to the right. This will shut off live steam from the top of 33x and the bottom of 33y and apply it to the bottom of 33x and the top of 33y etc. reversing the pumps until the cycle is 40 completed, when the main steam valve 81 will be returned to the position, as shown in Figs. 10, 11, as shown in the first position explanation.

In the fourth position (Figs. 15, 16 and 7), though the valve 78 is forced to the right as in 45 Fig. 14, valve 79 in being forced to the left, has rotated valve 78 by means of pin 94, so that port 105 (Fig. 7) is closed and the slot 101 now connects port 104 with port 106. Live steam from the passage 89 (Fig. 7) now follows the dotted 50 arrows through passage 106x, port 106, slot 101, port 104 under passage 75x into passage 88, and this steam presses against the outer face of piston 82, Fig. 8, moving main slide valve 81 to the right or towards piston head 38 thereby admitting 55 live steam to main port 86 with high pressure steam delivered to the top of piston 33y, reduced pressure to the bottom of piston 33x thereby reversing the pumping operation as required. The left piston is now on the down stroke and the 60 right piston 33x is on the up stroke.

In the fifth position (Fig. 17) the central valve 78 is moved to the left but does not rotate from the fourth position determination, as is shown by the non-rotation of pin 94 in the curved arrow 65 path 97. This movement to the left is caused

by right piston 33x first arriving at the top of its stroke and the tappet 90 shifts the slide valve 90B, that admits live steam to the outer face of piston 77. Slot 101, however, in travelling to the left has registered with ports 107 and 100, similarly to its previous registry over 106 and 104 of Fig. 7, thereby permitting live steam to follow the arrows from passage 89, through passage 107x, port 107, slot 101, port 100, passage 75x and back through passage 88 to the face of piston 82, keeping the main steam valve 81 as described 10 in its fourth position.

In the sixth and final position (Fig. 18) which may occur right after that of the fourth position, the left hand piston 33y has first arrived at the 15 bottom and the tappet 91 shifts the sliding valve 91B, causing live steam to flow into passage 110 and port 113 and moving piston 80 and pin 94 to the right. As will be seen the pin does not rotate and the center valve 78 remains as in the 20 fourth position. The slot 101 registers over ports 106 and 104, live steam still following the direction of the dotted arrows through ports, slot and passage 88 back to the piston 83 and keeps the main valve in the same position. Though the 25 left piston 80 has shifted to the right, there has occurred no rotation to prevent the center valve 78 from registering over the proper ports.

This completes the pumping cycle, as the next 30 piston movement would bring everything back to the starting point, as shown in the beginning. These six positions will be the same whether the inner valves 76 and 79 are shifted by steam or by mechanical means, such as the tappet rod and slotted hole device of Fig. 1.

It will be again noted that in Fig. 10 (first position) the main steam valve 81 remains at the left or towards piston 82, while in Fig. 15 (fourth position) it is shifted to the right. In 35 each case both pistons have completed their strokes, an ideal condition.

Should the second position intervene, nothing 40 happens until the lagging piston finishes and merges into the fourth position, causing an immediate reversal.

Also should the third position occur in place 45 of the second position, nothing happens until the other lagging piston finishes and also merges into the fourth position and causes a reversal.

The fifth or sixth positions are likewise intermediate between the fourth position and the following first position, and are as ineffective as the preceding second and third positions.

I claim:—

1. The combination of two double-acting steam 55 driven pumps having steam cylinders with a common steam supply and pump cylinders having common low pressure inlet valves and common low pressure outlet valves at corresponding ends of the pump cylinders, common high pressure 60 inlet valves and common high pressure outlet valves in the opposite ends of the pump cylinders, each steam cylinder and each pump cylinder having a piston, a single piston rod connecting one steam piston with a pump piston and a single 65 piston rod connecting the other pump piston with the other steam piston, said piston rods being operable independently of each other and being movable simultaneously in opposite directions, said piston rods being movable toward the steam 70 piston ends at a higher rate of speed than in the opposite direction, and means for supplying materially greater steam pressure to each steam piston when moving toward its pump cylinder than when moving in the opposite direction 75

whereby each pump piston pumps effectively against much greater pressure when moving in one direction than when moving in the opposite direction.

5. 2. The combination of a pair of pump cylinders, each having separate inlet and outlet passages, a double acting piston in each cylinder, a steam cylinder with a piston connected to each pump piston, a single auxiliary steam valve on top of 10 said steam cylinders and movable transversely thereon, a tappet-rod operated by each steam piston, each steam valve having an angular slot and said tappet-rods having pins engaging the said slots to mechanically actuate said steam 15 valves, a main steam valve controlled by the auxiliary steam valve and controlling the admission and exhaust of steam to and from said cylinders and a reducing valve interposed between the main valve and one end of each steam cylinder so as to provide for a material difference in 20 pumping pressure at the opposite ends of the pump cylinders.

3. A pump having two cylinders with separate 25 inlet and outlet passages and double-acting pump pistons movable simultaneously in opposite directions and at different speeds independently of each other, a steam driven piston for operating each pump piston, means for supplying a greater pressure to the steam pistons when moving in 30 one direction from that applied when moving in the other direction so as to enable each pump piston to pump against a greater pressure when moving in one direction than when moving in the opposite direction, valve mechanism for controlling the admission and exhaust of steam so 35 that each piston will arrive at one end of its stroke before the other piston arrives at the opposite end of its stroke and vice versa.

4. The combination of two double-acting 40 pumps, each having a cylinder with an inlet valve and an outlet valve at each end, a piston in each cylinder having a piston rod extending outside the upper end of the cylinder, each pump piston having a greater effective area on the 45 lower face than on the upper face, a steam cylinder on top of each pump, valve mechanism and connections for controlling the admission and exhaust of steam to and from both steam cylinders, a piston in each steam cylinder having a 50 piston rod connected to a pump piston rod, said steam pistons being movable independently, means of connection between the steam piston rods and said valve mechanism and reducing valves for supplying steam at a less pressure for the up strokes of the pistons than for the down strokes so as to provide greater pumping pressure on the down strokes of the pump pistons than on the up strokes.

5. A duplex pump construction comprising two 60 pump cylinders each having separate inlet and outlet passages and a double-acting pump piston, steam cylinders with pistons connected to the respective pump pistons, said steam pistons being movable alternately independently of each other in opposite directions and means for applying 65 materially greater unit pressure on one side of each steam piston than on its other side so that each pump piston pumps effectively against greater pressure in one direction than the other.

70. 6. A duplex pump construction comprising two pump cylinders each having separate inlet and outlet passages and a double acting pump piston, steam cylinders with pistons connected to the respective pump pistons, said steam pistons being 75 movable alternately independently of each other

in opposite directions, and means for applying materially greater unit pressure on one side of each steam piston than on its other side so that each pump piston pumps effectively against greater pressure in one direction than in the 5 other, each piston being provided with cushioning means, said cushioning means comprising a head for the pump cylinder provided with a cushioning recess at one end of the cylinder, said head having an inwardly projecting flange, the piston rod 10 passing through said head and the piston in the cylinder being connected to said rod and having a flange adapted to coact with the flange on the head so as to trap liquid within the cylinder recess. 15

7. A construction as set forth in claim 6 in which the head flange is provided with passages to allow for the escape of the trapped liquid.

8. A construction as set forth in claim 6 in which the flange of the piston surrounds the outside of the flange on the head at the completion 20 of the pumping stroke.

9. A construction as set forth in claim 5 provided with cushioning means for each pump piston, said cushioning means comprising a series 25 of outlet passages at one end of the pump cylinder, a flange on the piston reciprocable in the cylinder and adapted to at least partially close said passages at the end of the pumping stroke, said flange having passages to permit the escape 30 of air through the outer passages in the cylinder at the end of the stroke.

10. A double-liquid pump construction comprising two pump cylinders each having its own separate inlet and outlet valves and a pump piston, a steam cylinder with a piston and rod for each pump piston, each steam piston and its connected pump piston being movable independently of the other steam piston and its pump piston, means for causing each of said steam pistons and 40 connected pump pistons to start simultaneously, and cushioning means for at least one end of each pump piston comprising a series of outlet passages at one end of the pump cylinder, a flange on the piston reciprocable in the cylinder and 45 adapted to at least partially close said passages at the end of the pumping stroke, said flange having passages communicating with the outlet passages to permit the escape of air through the outlet passages in the cylinder at the end of the 50 stroke.

11. A double liquid pump construction comprising two pump cylinders each having its own separate inlet and outlet valves and a pump piston, a steam cylinder with a piston and rod for each pump piston, each steam piston and its connected pump piston being movable independently of the other steam piston and its pump piston, means for causing said steam pistons and their 60 connected pump piston to start simultaneously and cushioning means for at least one end of each pump piston comprising a head for the pump cylinder provided with a cushioning recess at 65 one end of the cylinder, said head having an inwardly projecting flange, and an outwardly projecting flange for supporting a stuffing box, the piston rod passing through said head and stuffing box and the piston in the cylinder being connected to said rod and having a peripheral flange adapted to coact with the inner flange on the head so as to trap liquid within the cylinder recess, the flange of the pump piston surrounding the outside of the inner flange of the head at the completion 70 of the pumping stroke.

12. A pump comprising a cylinder having a head 75

at one end with a cushioning recess therein, said head having an inwardly projecting flange, a piston rod passing through said head, a piston within the cylinder connected to said rod and having a flange adapted to coact with the flange on the head and to trap liquid within the cylinder, the head flange having a restricted passage to allow escape of trapped liquid, cushioning means at the other end of the cylinder, said means com-

prising a series of outlet passages in the cylinder wall, a flange on the piston reciprocable in the cylinder and adapted to at least partially close said passages at the end of the pumping stroke, said flange having passages to permit the escape of air through the outer passages in the cylinder wall at the end of the stroke. 5
